BERTHOLD JAHN, OF NEW BRITAIN, CONNECTICUT, ASSIGNOR TO GERTRUDE H. HEYN,
OF WESTPORT, CONNECTICUT.

STAPLING MACHINE.

Application filed September 22, 1926. Serial No. 136,928.

My invention relates to stapling machines, and more particularly to that class of machine in which a strip of connected staples is fed automatically to a point of cutting, at which point the staples are individually severed from the strip and driven by means of a plunger. In machines of this class it is the practice to provide a vertical channel for guiding the individual staple as it is severed from the strip down to the point where the staple enters the wood, paper or other material into or through which it is driven. The channel is defined by walls which control the movement of the severed staple and one wall of this channel also serves to limit the forward movement of the staple strip as it is fed forward at each operation to bring the end of the strip into position for the cutting operation. In some cases, through defective operation of the machine, or because of some defect in the staple, the severed staple becomes clogged in the guiding channel and this interferes with the operation of the machine. The object of my present invention is to provide simple and inexpensive means for removing a member which forms part of the guiding channel, in order to permit access to the staple which may have become clogged in the machine. Preferably, this removable member forms the forward member of the channel guide and it is so constructed that when in operative position it will effectively guide the severed staple as well as the lower end of the driving plunger. This member is adapted to be quickly released to provide access to the clogged staple, and in the preferred form of my invention the guiding member may be released without the use of tools.

In the drawing forming part of this application,

Figure 1 is a side elevation of a stapling machine of the character referred to having my invention applied thereto,

Figure 2 is a sectional view of a portion thereof taken on the line 2-2 of Figure 3,

Figure 3 is a sectional view taken on the line 3-3 of Figure 1, and

Figure 4 is a perspective view of the movable channel member detached from the machine.

In the drawing I have shown a well known type of stapling machine in which a pre-formed strip of connected staples is fed forwardly for the staples to be individually severed from the strip and driven. In the drawing I have shown only such parts of the complete machine as may be necessary to an understanding of the present invention. I have shown a base 1 having an anvil 2 formed at one end, against which the staples are adapted to be driven and clenched; and at the opposite end of the base there are upstanding ears 3 to which the cutter bar of the machine is pivoted by means of the pin 4. The cutter bar 5 along which the strip of staples is guided is of the usual construction and is mounted upon the pivot pin 4. The housing or casing 6 encloses most of the mechanism of the machine and it forms a guide for the plunger 7 which is vertically movable in the forward end of the casing. There is a knob 8 on the upper end of this plunger which is adapted to be struck by the hand in order to drive the plunger downwardly to sever and clench the staples; and the return operation of the plunger is effected by the coiled spring 9 acting between the top of the frame and the knob. The strip of staples 10 of well known form and of U shape in cross section, is fed along the top of the cutter bar 5 so that the back of the strip rests on top of the cutter bar, and the prongs of the staples project downwardly on each side thereof, as shown in Figure 2. The staple strip is fed forwardly the width of one staple at each operation of the plunger by means of the feed pawl 11 which is pivoted at 12 upon the cam plate 13 which itself pivots upon the pin 14. This plate has a cam portion 15 which is acted upon by the plunger to oscillate the plate 13 for the purpose of operating the feed pawl. The forward end of the detent 16 is also indicated in the drawing, this member serving to prevent the retraction of the staple strip while the feed pawl is moving back to engage behind a pair of prongs ready for the feeding operation. All of the above parts are of well known construction and are usually incorporated in the various stapling machines now on the market.

When the staple strip is moved forwardly

into position for the severing operation the forward end of the strip overhangs the cutter bar 5 to an extent corresponding with the width of a single staple and the vertical 5 guiding channel is in alignment with this portion of the staple which overhangs the cutter bar. In the construction shown in the drawing this channel is partly defined by the members 17, 18 of the frame or housing 10 which constitute the side walls of the channel. The rear wall of this channel is composed of the cutter bar 5 and partly by the side rails 19 which separate the cutter bar from the side walls 17, 18 of the casing but 15 which terminate below the ends of the prongs of the staple strip as the same travels along the top of the cutter bar. The remainder of the guideway is composed of the movable member which forms the subject 20 matter of my present invention and which is constructed as follows: There is a plate 19 which may be stamped of sheet metal and it comprises side portions 20, 21 which are adapted to straddle the side faces of the 25 frame members 17, 18; and a connecting wall 22 extending between the two side walls. This connecting wall is preferably formed to provide the inwardly extending portions 23 at each side, arranged at right angles to 30 the side walls 20, 21 and from there the metal extends outwardly at right angles to form the walls 24 and a connecting wall 25. This construction provides an offset pocket in which the vertical rib 26 of the plunger 35 is adapted to travel, and in which it is adapted to be guided. One of the side walls 20 of the member 19 is provided with a slot 27 to receive the projecting end of the pin 28 40 which projects from one side 17 of the casing. The other side wall 21 of this member is also provided with a slot 29 to receive a shank of the headed pin 30 which projects from the opposite side wall 18 of the casing. There is a lever pivoted at 31 to the side wall 45 21 and it is provided with a finger piece 32 at one end, and adjacent its pivotal point it is provided with a hook 33 to engage over the shank of the pin 30.

To apply the movable guide member to 50 the casing the lever 34 is raised, as shown in Figure 4, and the member 19 is slipped over the forward ends of the casing members 17, 18 so that the pins 28, 30 are received within the slots 27, 29. The lever 34 is then swung 55 down until the hook 33 engages over the pin 30 whereupon the movable guide member will be attached in place ready for operation; and it will remain in this position until such time as it may be necessary to 60 remove a staple which has become clogged in the guide-way.

When the staple strip is moved forwardly in the feeding operation, the forward end of the strip will stop against the portions 23 65 of the member 19 and this will define the

feeding position of the strip. When the plunger is struck by the hand it moves downwardly until the bottom edge of the plunger co-operates with the cutter bar 5 to sever the projecting staple from the strip, and as the 70 plunger continues downwardly the severed staple is guided in the raceway until it is forced into or through the paper or other material into which the staple is to be driven. While the severed staple is moving 75 downwardly, it is guided on the forward side by means of the member 19 and more particularly by the portions 23 and on other sides the staple is guided by the frame members 17, 18 and the cutter bar, so that it is maintained in a vertical position while it is being driven. When the plunger moves 80 downwardly the projecting rib 26 thereof is guided in the pocket 35 formed by the offset portion of the member 19, the same as if this member constituted a rigid portion of the frame proper. The pins 28, 30, together with the hook 33 retain the member 19 rigidly in place against the end of the frame, so that this member serves the same function 85 as if it were formed as an integral part of the frame. If the staple should become clogged in the raceway, or jammed, then the member 19 may be detached in order to open the lower end of the raceway and either permit the clogged staple to fall out or to permit the operator to dislodge it. To remove the member 19 the lever 34 is raised to release the hook 33 from the pin 30 whereupon 90 the member 19 may be moved to the left in Figure 2 until the portions 20, 21 disengage from the pins 28, 30. It will be apparent 95 that this movable member forming part of the raceway, permits ready access at all times to a clogged staple.

Having described my invention, what I claim is:

1. In a stapling machine in which a pre-formed strip of staples is fed forwardly, the combination with a frame, a cutter bar for guiding the strip of staples to the cutting position, said frame and cutter bar being fixed in relation to each other, a plunger for severing and driving the end staple of the strip and movable at right angles to the cutter bar, a raceway for guiding the severed staple formed partly by said frame, and a front member, and means for holding said front member on said frame, including pins on the frame adapted to be received in slots in said front member, and a lever pivoted to said front member and adapted to be hooked over one of said pins for locking said front member upon said casing.

2. In a stapling machine in which a pre-formed strip of staples is fed forwardly, the combination with a frame, a cutter bar for guiding the strip of staples to the cutting position, said frame and cutter bar being fixed in relation to each other, a plunger for

severing and driving the end staple of the strip and movable at right angles to the cutter bar, and a raceway for the severed staple formed partly by said frame, a front member also forming part of said raceway, having side walls for straddling the frame, said side walls having slots, pins on said frame adapted to be received in said slots, and a lever pivoted to said front member and adapted to hook over one of said pins for locking the front member to the frame. Signed at New Britain, county of Hartford, State of Connecticut, this 18th day of September, 1925.

BERTHOLD JAHN.
